UNITED STATES PATENT OFFICE.

CARL POLSON, OF VERMILLION, KANSAS.

END-GATE FOR WAGONS.

1,242,860.

Specification of Letters Patent.

Patented Oct. 9, 1917.

Application filed September 1, 1916. Serial No. 118,108.

To all whom it may concern:

Be it known that I, CARL POLSON, a citizen of Sweden, residing at Vermillion, in the county of Marshall and State of Kansas, have invented new and useful Improvements in End-Gates for Wagons, of which the following is a specification.

This invention relates to improvements in end gates for wagons and has particular application to an end gate which may be used as a scoop board when desired, the present invention being in the nature of an improvement upon the construction disclosed in my former Patent No. 1,173,857, issued Feb. 29, 1916.

In my previous patent, above referred to, the end gate is held in position at the rear end of the wagon body by means of vertical securing strips pivoted to the inner surface 20 of the end gate adjacent to the respective ends thereof and normally projecting at right angles to the end gate and having the outer surface formed with vertical ribs respectively designed to engage in ways 25 formed between pairs of vertical guide strips secured to the inner faces of the respective side boards of the wagon box, at the rear end thereof. These vertical securing strips are capable of inward swinging 30 movement onto the rear face of the end gate and when swung inwardly the ribs are moved out of the guide ways between the guide strips so that the latter may be removed from the wagon box. The vertical 35 securing strips are connected to the inner ends of levers that work in slots formed in the respective extremities of the end gate and the other ends of these levers are disposed upon the outer side of the end gate 40 and when the levers are swung in one direction the vertical securing strips are actuated to release the gate, while when the levers are actuated in the other direction, the ribs on the securing strips are connected in the 45 spaces between the guide strips to hold the end gate in position.

In the present invention, these actuating levers are connected to rods and the rods are, in turn, connected to a single actuating bar so that when the bar is swung in one direction both levers are operated to release the gate, while when the bar is swung in the other direction, the levers are actuated to hold the gate. Thus, both levers are controlled from a single bar, thereby enabling the gate to be quickly and conveniently se-

cured in position and released. This operating bar is equipped with suitable locking means whereby the levers may be locked in holding position so as to prevent accidental 60 disconnection of the end gate from the wagon body.

The invention also contemplates the provision of novel means for holding the sections of the end gate together when swung 65 to scoop formation and of improved hinge connections between the lower edge of the end gate and the bottom of the wagon body so that the end gate may be swung to scoop forming position, or detached from the 70 wagon box.

The invention consists in the construction, combination and arrangement of parts hereinafter set forth in and falling within the scope of the appended claims.

In the accompanying drawings:

Figure 1 is a rear end view of a wagon box equipped with an end gate constructed in accordance with the present invention.

Fig. 2 is a fragmentary top plan view of 80 the same.

Fig. 3 is a fragmentary longitudinal sectional view through the box and end gate.

Fig. 4 is a fragmentary transverse sectional view therethrough.

Fig. 5 is a similar view taken at right angles to Fig. 4.

Fig. 6 is a fragmentary side elevation showing the means for reinforcing the side boards of the wagon box and the means for holding the end gate in scoop forming position.

Referring now to the drawings in detail, 1 designates a wagon box of any suitable construction. Secured to the inner faces of the side boards of the box 1 at the rear ends thereof are pairs of vertical guide strips 2, the strips of each pair being spaced apart to form a guide way. 3 designates an end gate designed to close the rear end of the 100 box 1 and of a length to fit nicely between the side boards of the wagon box. Pivoted to the inner surface of the end gate 3 adjacent to the respective ends thereof are vertical securing strips 4 normally projecting at right angles to the end gate and having the outer surfaces formed with vertical ribs 5 designed to engage in the ways between the strips 2 when the securing strips are at right angles to the end gate so as to 110 hold the end gate in position at the rear end of the wagon box. These strips 4 are capable

of inward swinging movement onto the rear surface of the end gate and when swung inwardly the ribs 5 are moved out of the 5 guide ways between the guide strips 2 to release the end gate so that the latter may be removed from the wagon box. In the present instance, the respective extremities of the end gate 3 are formed with slots 6 and working within the slots 6 are levers 7, 10 each having one end fastened to the proximate edge of the adjacent strip 4 and the other end portion disposed upon the outer side of the end gate. These levers 7, when swung outwardly from the end gate, actuate the strips 4 inwardly onto the inner surface 15 of the end gate, to release the latter, while when the levers are swung toward the outer surface of the end gate, the strips 4 are swung outwardly to engage the ribs 5 in the 20 ways between the guide strips 2.

In the present instance, the end gate 3 is formed of top and bottom sections 8, 8 respectively and these sections are identical in construction and equipped, respectively, 25 with the securing strips and the levers. Extending across the outer side of each section are rods 9, 9 having the outer ends formed to engage the outer surfaces of the side boards of the wagon at the rear end thereof 30 and the inner ends pivotally connected to an operating bar 10. The rods 9, 9 are pivotally connected to the outer ends of the respective levers 7 so that when such rods are moved in one direction under the action of the bars 10, 35 the levers will be actuated to disengage the ribs from the guide ways and move the outer ends of the rods out of engagement with the side boards of the wagon, thereby releasing the end gate. On the other hand, 40 when the bar 10 is swung in the opposite direction, the rods 9 are actuated to swing the levers and the supporting strip to engage the ribs in the spaces between the guide strips, and the outer ends of the rods 45 engage the side boards of the wagon, thereby securely fastening the end gate in position at the rear end of the wagon body. In the present instance, one edge of the bar 10 is formed with notches 11, while mounted 50 upon one of the rods 9 is a strap iron 12 designed to engage the notched edge of the bar to hold the latter in end gate locking position.

The lower edge of the bottom section of the end gate at the corners thereof is cut 55 out and in these cut out portions are horizontally disposed sleeves 13 carried by plates 13' secured to the lower edge of the bottom section of the end gate and acting to close the cut out portion. Rotatably mounted in 60 each sleeve 13 is a rod 14 having one end projecting out of the sleeve and formed with a transverse bore 15. Rotatably mounted in each bore 15 is a rod 16 having one end formed to provide a lug 17 adapted to engage in the lower end of the adjacent way

formed by the strips 2 and the outer end 70 formed to provide a handle 18. When the rods 16 are swung in one direction under the action of the handles 18 the lugs 17 engage in the lower ends of the ways formed 75 by the strips 2 below the ribs 5 and so hold the rods 14 to the wagon box so that the end gate may be swung outwardly and downwardly when relieved of the influence 80 of the ribs 5 on the strips 4. On the other hand, when the rods are swung in the opposite direction under the action of the handles, the lugs 17 are moved out of the respective 85 guide ways so that the end gate may be bodily removed from the wagon body when the holding ribs 5 are withdrawn from the respective guide ways under the action of the levers 7, rods 9 and bars 10.

In order to hold both sections 8, 8 of the end gate so that such sections may be moved simultaneously, levers 19, 19 are pivoted between their ends adjacent to the respective extremities of the upper section of the end gate and one edge of each lever adjacent to the upper end thereof is formed with a notch 20, while the opposite end, adjacent to the lower edge, is formed with a notch 21. When the levers 19 are swung across the sections of the end gate the upper notches 20 engage pins 22 carried by the top section, 90 while the lower notches engage pins 23 carried by the bottom section. Each pin 23 is preferably guarded by a plate 24 that is spaced apart from the adjacent portion of the end gate to form a space to receive the 95 corresponding end of the lever. When the levers 19, 19 are in inactive position, they extend across the top section of the end gate and are arranged end to end and the notches 21 engage lugs 25 on the top section of the 100 end gate to hold the levers against accidental movement.

The members 26 prevent accidental disconnection of the rods 14.

Detachably connected to the inner surface 110 of the end gate adjacent to the respective vertical edges thereof are guards 27 that act to guide the material along the end gate when the latter is swung to scoop board position. 28, 28 indicate rods, each having one 115 end formed with a hook engaged in a bearing 30 carried by the top section of the end gate and the other end portion passed through the legs of a U-shaped support 31 pivoted upon the adjacent side board of the 120 wagon at the upper edge thereof. These rods 28 are formed with transverse openings in which are mounted cotter pins that engage the U-shaped supports 31 when the end gate is swung downwardly to limit the 125 downward movement of the end gate. When the gate is swung upwardly, the rods 28 swing in the bearings 30 and the supports 31 swing about their pivotal connections with the side boards of the wagon so that the rods 130

28 may be disposed in vertical position when the end gate is closed.

In the present instance, an additional section is secured to the upper edge of the upper section 8 and this additional section carries the bearings 30.

While I have herein shown and described the preferred form of my invention by way of illustration, I wish it to be understood 10 that I do not limit or confine myself to the precise details of construction herein described and delineated, as modification and variation may be made within the scope of the claims and without departing from the 15 spirit of the invention.

I claim:

1. In end gate construction, the combination with a vehicle body, of an end gate mounted on the bottom of the body between 20 the sides thereof and hinge connections between said end gate and sides of the body, each connection comprising a horizontal rod rotatably secured to the end gate adjacent its lower edge, a second rod secured to and extending at right angles with said first mentioned rod, said second mentioned rod being

formed on its inner end with means for engagement with the side of the body, the second mentioned rod being rotatable to disengage said last mentioned means from the 30 body.

2. In end gate construction, the combination with a vehicle body having vertical channels formed on the side walls thereof, of an end gate having its lower corners cut 35 away to form recesses and hinge connections between said end gate and body, each connection comprising a sleeve positioned in one of said recesses and having a horizontal axis, a rod rotatably mounted in said sleeve 40 extending beyond one end thereof and lying entirely within said recess, the rod being formed in its projected end with a transverse opening, a shaft extending through said transverse opening having a crank handle on one end thereof, and means on the other end of said rod for removable engagement in one of the channels formed on the side walls of the body.

In testimony whereof I affix my signature. 50

CARL POLSON.
